UNITED STATES PATENT OFFICE.

CHARLES LEWIS SCHWARZ, OF PHILADELPHIA, PENNSYLVANIA.

VEHICLE-SPRING.

1,182,218.

Specification of Letters Patent.

Patented May 9, 1916.

Application filed April 17, 1913, Serial No. 781,669. Renewed July 28, 1914. Serial No. 853,692.

To all whom it may concern:

Be it known that I, CHARLES L. SCHWARZ, a citizen of the United States, residing in the city and county of Philadelphia, State 5 of Pennsylvania, have invented a new and useful Vehicle-Spring, of which the following is a specification.

My invention consists of an improved vehicle spring in which the rebound of the spring is absorbed to prevent sudden shocks and the main spring is reinforced.

It further consists of other novel features of construction, all as will be herein-after fully set forth.

15 The annexed drawings and the following description set forth in detail one mechanical form embodying the invention, such detail construction being but one of various mechanical forms in which the principle of 20 the invention may be used.

25 In said annexed drawings—Figure 1 represents a side elevation of a spring embodying my invention. Fig. 2 represents a side elevation of another form of spring embodying the invention. Fig. 3 represents a side elevation of still another form of spring embodying the invention. Fig. 4 represents a side elevation showing a form of central support or bearing which may be employed.

30 Similar numerals of reference indicate corresponding parts in the figures.

Referring to the drawings, the reference numbers 1 indicate supports, such as hangers or brackets secured to the body of the 35 vehicle or chassis of a motor carriage, which hangers or brackets may, however, form parts of the vehicle frame. Pairs of links, 2, are pivotally supported upon said brackets, and the ends of a main spring, 3, of the 40 usual so-called elliptic shape and having downwardly curved ends, are pivotally supported upon bolts, 4, between the pairs of links. The axle, 5, for the vehicle-wheels is secured by shackles, 6, and a bar, 7, to said 45 main spring at about the middle of the same. A bar or yoke, 8, is secured beneath the main spring and two pairs of links, 9, are pivotally connected to the ends of said bar. The inner ends of two auxiliary springs, 10, 50 are pivotally connected to the lower ends of said pairs of links, and are pivotally connected at their outer ends to the links upon the brackets, and shackles, 11, and bars, 12, connect the middles of said springs and the 55 branches of the main-spring, such shackles

being capable of sliding upon the main spring.

The main spring and the auxiliary springs are preferably leaf-springs, such as are ordinarily employed for vehicle springs, but it 60 is evident that the springs may be formed from one leaf, only, or from as many leaves as the load to be supported requires.

In Fig. 1 of the drawings, the end-links are shown as pivoted at their lower ends to 65 the brackets, the ends of the main spring are shown as pivoted to the middles of the links, and the outer ends of the auxiliary springs are shown as pivoted to the upper 70 ends of the links.

In Fig. 2 of the drawings, the end-links are shown as pivoted at their middles to the brackets, the ends of the main spring are shown as pivoted to the upper ends of such 75 links, and the outer ends of the auxiliary springs are shown as pivoted to the lower ends of the links.

In Fig. 3 of the drawings, the end-links are shown as pivoted at their upper ends to the brackets, the ends of the main spring are shown as pivoted to the middles of the 80 links, and the ends of the auxiliary springs are shown as pivoted to the lower ends of the links.

85 In the construction shown in Fig. 4, instead of having said suspension links pivotally suspended from the ends of a bar or yoke rigidly secured to the axle, as in the forms of Figs. 1, 2 and 3, said links are suspended from the ends of yokes, 13, which are fulcrumed upon the axle. As illustrated, the axles are cylindrical where the yokes bear, as at 14, and the yokes are formed with annular bearings, 15, encircling such portions.

90 In the different forms of the invention, strain upon the ends of the main spring is partly borne by the auxiliary springs and any rebound from compression strain upon the main spring will be resisted by said auxiliary springs. The shackles connecting the end-portions of the main spring and the middles of the auxiliary springs have longitudinal play upon the main spring to admit of said springs flexing independently. The link-connections admit of free movement of the springs, but prevent lateral movement of the same. While the auxiliary springs assist in carrying the load upon the main spring, they do not interfere with the 10 11

resiliency of the latter, as there is free play between the springs, so that they can flex or yield independently, and the link-supports for said springs admit of such free and independent movement, whereby it will be seen that by reason of the independent flexing and play between the springs, the bearing surface between the branches of the main spring and the auxiliary springs, varies, depending upon the load, that is to say, as the load increases, it will be apparent that a greater bearing surface exists between the branches of the main spring and the said auxiliary springs, by means of which the proper resiliency will be maintained at the same time the strength of the structure will be maintained and with a reduction of weight, so that bumping and other objectionable features will be avoided. When the load decreases, the bearing surface between the springs will be lessened, as will be evident, so that by the structure, the springs will retain the proper resiliency, whether under a full load or none.

When the auxiliary springs have their inner ends movably supported from the ends of movable yokes, as illustrated in Fig. 4, it is evident that the strain of either branch of the main spring will be communicated to the auxiliary spring at that side and that said spring will in turn communicate a portion of such strain to the auxiliary spring on the other side of the axle, through the pivoted yokes, which spring, in its turn, communicates the strain to the other branch of the main spring, strain being thus distributed over the entire spring-structure.

The effect of the connection of the auxiliary springs with the main spring as described, is that the flexure or bend of the main spring under load, as the body approaches the axle, will also flex the auxiliary springs, with the result that the resistance to bend of the auxiliary springs will be added to that of the main spring, and will thus resiliently reinforce the same. In other words, the flattening of the main spring under load, will be accompanied by a relatively increasing resistance to distortion of the auxiliary springs, resulting in a final total resistance of the entire spring system in increasing ratio. In the rebound of the body from the axle, the main spring will be relieved of its tension and its concavity will be increased, while at the same time the auxiliary springs will also be released, and as the separation of the parts of the vehicle continues, the auxiliary springs will become flattened and will thus oppose, in increased ratio, the rebound of the body, and will effectually check it. It is seen therefore that my improved form of spring, while increasing the load bearing capacity of the body, will prevent objectionable rebound, and this without interfering with the resiliency of

the support afforded the body, or impairing the consequent easy riding qualities of the same.

While this spring is principally designed for motor-driven vehicles, in which the recoil or rebound of the springs in passing over obstacles in the road is especially detrimental and obnoxious, it is evident that the spring may be applied to any wheeled vehicle. It is also evident that the brackets, while here illustrated as detached and capable of being secured to the frame or chassis of the vehicle, may form integral parts of such frame or chassis.

Other modes of applying the principle of my invention may be employed for the mode herein explained. Change may therefore be made as regards the mechanism thus disclosed, provided the principles of construction set forth respectively in the following claims are employed.

Having thus described my invention, what I claim as new and desire to secure by Letters Patent, is:

1. In a device of the character stated, supports, links pivotally connected to such supports, a main spring having its ends pivotally connected to said links, an axle having such spring supported upon it, and auxiliary springs pivotally connected at their outer ends to said links and pivotally supported at their inner ends at about the middle of the main spring and bearing against the branches of the latter, said branches and auxiliary spring being longitudinally slidably connected.

2. In a device of the character stated, supports, links pivotally connected to such supports, a main spring having its ends pivotally connected to said links, an axle having said spring supported upon it, links pivotally supported from said axle, auxiliary springs having their inner ends pivotally connected to said links and their outer ends pivotally connected to the first named links and having their middles bearing against the branches of the main spring, and shackles slidably connecting said branches and the auxiliary springs.

3. In a device of the character stated, supporting brackets, pairs of links pivotally connected to said brackets, a main spring having its ends pivoted between said pairs of links, an axle having said main spring supported upon it, pairs of links pivotally supported from said axle, auxiliary springs having their inner ends pivotally supported between said pairs of links and their outer ends pivotally supported between the pairs of links on the brackets and having their middles bearing against the branches of the main spring, and shackles slidably connecting said branches and auxiliary springs.

4. In a device of the character stated, supports, links pivotally connected to such

supports, a main spring having its ends pivotally connected to said links, an axle having said spring supported upon it, yokes pivoted upon said axle, links pivotally suspended from the ends of said yokes, auxiliary springs having their inner ends pivotally connected to said links and their outer ends pivotally connected to the first named links and having their middles bearing against the branches of the main spring, and shackles slidably connecting said branches and the auxiliary springs.

5. In a device of the character stated, a main spring having its ends movably supported, and auxiliary springs having their outer ends movably supported and their inner ends pivotally supported and bearing against the branches of the main spring, said branches and auxiliary springs being longitudinally slid able.

6. In a device of the character stated, a main spring having branches, auxiliary springs bearing against said branches, and means for movably supporting said main spring and said auxiliary springs in suitable slid able relation to each other, whereby the bearing surface therebetween, varies, depending upon the load.

7. In a device of the character stated, supports, a main spring having its ends movably carried by said supports, and auxiliary springs movably carried at their outer ends by said supports and movably supported at their inner ends and bearing against the branches of the main spring, said branches and auxiliary springs being longitudinally slid able.

8. In a device of the character stated, supports, a main spring having its ends pivotally connected to said supports, and auxiliary springs pivotally connected at their outer ends to said supports and pivotally supported at their inner ends and bearing against the branches of the main spring, said branches and auxiliary springs being longitudinally slid able.

9. In a device of the character stated, supports, links pivotally connected to said supports, a main spring having its ends pivotally connected to said links, and auxiliary springs pivotally connected at their outer ends to said links and pivotally supported at their inner ends and bearing against the branches of said main spring, said branches and auxiliary springs being longitudinally slidably connected.

10. In a device of the character stated, supports, links pivotally connected to said supports, a main spring having its ends movably carried by said links, an axle having the main spring supported upon it, a bearing fulcrumed upon the axle, and auxiliary springs movably carried at their outer ends by the first named links and pivotally supported at their inner ends upon the

bearing, said auxiliary springs contacting with the branches of the main spring, and said branches and auxiliary springs being longitudinally slid able.

11. In a device of the character stated, supports, links pivotally connected to said supports, a main spring having its ends pivotally connected to said links, an axle having a main spring supported upon it, a yoke fulcrumed upon the axle, links pivotally supported from said yoke, and auxiliary springs pivotally connected at their outer ends to the first named links and pivotally supported at their inner ends upon the last named links and bearing against the branches of the latter, said branches and auxiliary springs being longitudinally slid able.

12. A vehicle spring comprising a curved main leaf spring adapted to be supported by the axle of the vehicle, and an auxiliary leaf spring of opposite curvature to and of less length than the main spring, said auxiliary spring being connected at its inner end with the main spring between the ends of the latter, and being connected at its outer end to one end of the main spring, said end of the main spring being adapted to be connected with the vehicle body independently of the auxiliary spring.

13. A vehicle spring comprising a main curved leaf spring adapted to be supported by the axle of the vehicle, and an auxiliary leaf spring of opposite curvature to and of less length than the main spring, said auxiliary spring being supported between its ends by the main spring, the inner end of the auxiliary spring being connected with the main spring between the ends of the latter, and the outer end of the auxiliary spring being connected to one end of the main spring, said end of the main spring being adapted to be connected with the vehicle body independently of the auxiliary spring.

14. A vehicle spring comprising a main curved leaf spring adapted to be supported by the axle of the vehicle, and an auxiliary leaf spring of opposite curvature to and of less length than the main spring, said auxiliary spring being movably supported between its ends by the main spring, the inner end of the auxiliary spring being connected with the main spring between the ends of the latter, and the outer end of the auxiliary spring being connected to one end of the main spring, said end of the main spring being adapted to be connected with the vehicle body independently of the auxiliary spring.

15. A vehicle spring comprising a curved main leaf spring adapted to be supported by the axle of the vehicle, and an auxiliary leaf spring of opposite curvature to and of less length than the main spring, said auxiliary spring being movably connected at its inner

4
end with the main spring between the ends of the latter, and being movably connected at its outer end to one end of the main spring, said end of the main spring being adapted to be connected with the vehicle body independently of the auxiliary spring.

16. A vehicle spring comprising a curved main leaf spring adapted to be supported by the axle of the vehicle, and an auxiliary leaf spring of opposite curvature to and of less length than the main spring, said auxiliary spring being movably supported between its ends by the main spring, the inner end of the auxiliary spring being movably connected with the main spring between the ends of the latter, and the outer end of the auxiliary spring being movably connected with one end of the main spring, said end of the main spring being adapted to be connected with the vehicle body independently of the auxiliary spring.

17. A vehicle spring comprising a curved main leaf spring adapted to be supported by the axle of the vehicle, and two auxiliary leaf springs of opposite curvature to the main spring, the inner ends of said auxiliary springs being connected with the main spring between the ends of the latter, and the outer ends of the auxiliary springs being connected with the outer ends of the main spring, said ends of the main spring being adapted to be connected with the vehicle body independently of the auxiliary springs.

18. A vehicle spring comprising a main curved leaf spring adapted to be supported between its ends by the axle of the vehicle so as to constitute in effect two spring branches, and an auxiliary leaf spring associated with each of the said branches, the inner ends of the auxiliary springs being connected with the inner ends of the branches of the main spring, and the outer ends of the auxiliary springs being connected with the outer ends of the branches of the main spring, said outer ends of the main spring being adapted to be connected with the vehicle body independently of the auxiliary springs.

19. A vehicle spring comprising a curved main leaf spring adapted to be supported by the axle of the vehicle, and two auxiliary leaf springs of opposite curvature to the main spring, said auxiliary springs being supported between their ends by the main spring, the inner ends of said auxiliary springs being connected with the main

spring between the ends of the latter, and the outer ends of the auxiliary springs being connected with the outer ends of the main spring, said outer ends of the main spring being adapted to be connected with the vehicle body independently of the auxiliary springs.

20. A vehicle spring comprising a curved main leaf spring adapted to be supported by the axle of the vehicle, and two auxiliary leaf springs of opposite curvature to the main spring, said auxiliary springs being movably supported between their ends by the main spring, the inner ends of the auxiliary springs being movably connected to the main spring between the ends of the latter, and the outer ends of the auxiliary springs being movably connected with the outer ends of the main spring, said outer ends of the main spring being adapted to be connected with the vehicle body independently of the auxiliary springs.

21. A vehicle spring comprising a main leaf spring adapted to be supported by the axle of the vehicle, and an auxiliary leaf spring of less length than the main spring, a link connecting the inner end of said auxiliary spring with the main spring between the ends of the latter, and a link connecting the outer end of the auxiliary spring with one end of the main spring, said end of the main spring being adapted to be connected with the vehicle body.

22. A vehicle spring comprising a main leaf spring adapted to be supported by the axle of the vehicle, and two auxiliary leaf springs, links connecting the inner ends of said auxiliary springs with the main spring between the ends of the latter, and links connecting the outer ends of the auxiliary springs with the ends of the main spring, said ends of the main spring being adapted to be connected with the vehicle body.

23. A vehicle spring comprising a curved main leaf spring, and two auxiliary leaf springs of opposite curvature contacting between their ends with the main spring, links connecting the inner ends of the auxiliary springs to the main spring between the ends of the latter, and links connecting the outer ends of the auxiliary springs to the outer ends of the main spring.
